EXERCISER

Alfred P. Brandimarte and Jack E. Herweg, Fort Worth,
Tex., assignors to A.R.A. Manufacturing Company,
Grand Prairie, Tex.

Application December 19, 1958, Serial No. 53,827

Term of patent 14 years

(Cl. D83—1)

Fig. 4.

Fig. 2.

Figure 1 is a perspective view of an exerciser, showing our new design;

Figure 2 is a side elevational view thereof;

Figure 3 is a top plan view; and

Figure 4 is a vertical sectional view, taken substantially in the plane of the line 4-4 in Figure 2.

The appearance of the side opposite to that shown in Figure 2 is substantially the same as that of the side illustrated.

We claim:

The ornamental design for an exerciser, as shown and described.
